UNITED STATES PATENT OFFICE.

HORACE P. STEWART, OF GRAND RAPIDS, MICHIGAN.

DESIGN FOR A CLASP.

42,114.

Specification for Design.

Patented Jan. 23, 1912.

Application filed September 12, 1911. Serial No. 648,974. Term of patent 7 years.

To all whom it may concern:

Be it known that I, HORACE P. STEWART, a citizen of the United States, residing at Grand Rapids, in the county of Kent and State of Michigan, have invented a certain new, original, and ornamental Design for a Clasp, of which the following is a specification, reference being had therein to the accompanying drawing.

Figure 1 is a perspective view of the sections drawn apart. Fig. 2 is a perspective view of the sections connected together.

What is claimed is:

The ornamental design for a clasp, as shown.

In testimony whereof I hereunto affix my signature in presence of two witnesses.

HORACE P. STEWART.

Witnesses:

IRVING H. STROUR,
FRANK E. STROUR.
